(57) **CLAIM**

The ornamental design for a generated image for display on a personal digital assistant, as shown and described.

DESCRIPTION

The file of this patent contains at least one drawing executed in color. Copies of this patent with color drawings will be provided by the Office upon request and payment of the necessary fee.

FIG. 1 is a top front perspective view of a generated image for display on a personal digital assistant showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlargement of the image area shown in FIG. 2. The broken line showing of a personal digital assistant is included for the purpose of illustrating portions of the article and forms no part of the claimed design.
